DAVID S. BAKER, OF GREENWICH, CONNECTICUT.

DRIER.

Application filed June 29, 1926. Serial No. 119,301.

This application relates to driers for evaporating moisture from various materials, such as paints, paint materials, chemicals and other substances, and particularly to the type 5 of driers in which a stream of drying medium is retained at the proper temperature and the moisture content by passing it over re-heaters between its successive contacts with masses of the material to be dried.

10 An object of the invention is to provide a new means for controlling the reheating of the drying medium which permits a simplification of the construction of such driers. A further object is to provide for the use of flue 15 pipes containing products of combustion both for preheating and reheating the drying medium.

The invention is of a special value when applied to the so-called "Gordon" type of drier, 20 shown for example in U. S. Patents Nos. 1,405,780 and 1,504,854, in which the drying medium is passed at high linear velocity through a tortuous passage formed by staggered overlapping flow directing members in 25 a drying chamber. In such driers, the temperature of the drying medium throughout its course through the tortuous passage has been controlled by regulating the supply of heating medium to, and thus the heat of, each 30 reheater. This arrangement necessitates the expense of a separately controlled heater at each point at which the drying medium is to be reheated, and of course, precludes the use of flue pipes as a reheating means.

35 In accordance with the present invention, the reheating of the drying medium is controlled by regulating the proportion of the stream of drying medium which comes in contact with each reheater, so that the heat absorbed by the drying medium from each reheater may accurately be controlled without varying the amount of heating medium supplied to the reheaters. This makes possible the use of a single heating element to reheat 40 the drying medium at several different points in its course, and thus facilitates the use of flue pipes for reheaters.

This and other features may best be understood from a detailed description of a specific 50 drier of the "Gordon" type embodying the

invention which is shown in the accompanying drawings, in which:

Fig. 1 is a front elevation of the drier sectioned on the line 1—1 of Fig. 2 and Fig. 3;

Fig. 2 is a plan view of the top of the 55 drier; and

Fig. 3 is a horizontal section taken on the line 3—3 of Fig. 1.

The drier illustrated has a rectangular casing 10 most desirably constructed of insulating material. In the casing is an open rack 11 supporting oppositely facing angle irons 12 for holding a series of superimposed horizontal trays 13 for supporting masses of the material to be dried. The front of the casing contains a door 14 through which the trays 13 may be removed.

Air or other drying medium is forced into the chamber by a blower 15, whose discharge is connected by an expanding conduit 16 with 70 an inlet opening 17 at the top of the casing near one of its side walls. After circulating within the casing in the manner hereinafter described, the air may be discharged through a valve controlled outlet opening 18 in the 75 casing, or all or a part of it may be recirculated by drawing it back into the blower through a valve controlled opening 19 in the top of the casing.

A fire box 20 is located in one side of the 80 casing near its bottom. The fire box may contain a gas burner 21, and may be supplied with air through an opening 22 in the bottom of the casing. From the top 23 of the fire box, two sets of flues 24, 25 extend vertically 85 upward through the casing at one side of the rack 11. These flues extend out through the top of the casing and pass through the conduit 16. Their upper ends may be connected by a hood 26 with a chimney 27. It will be 90 understood that as the products of combustion from the fire box 20 pass through the flues 24, 25, the lower portions of the flues are hotter than the upper portions thereof. The heat and the flow of the flue gas may be 95 retained constant throughout the operation of the drier.

The lowest tray 13' is on a level with the top 23 of the fire box, and co-operates with the top of the fire box and a partition 28 in 100

providing the bottom of a chamber 30 in which the drying medium is circulated. By means of the flow directing members herein-after described, there is formed in this chamber a long flow passage having a descending portion 31 in which the drying medium is preheated, and a tortuous ascending portion 32 in which the drying medium passes over the material to be dried, and in the bends 10 of which it is reheated. The descending and ascending parts of the flow passage are separated by a partition 33 having an upper vertical portion 34 located between the outer flue pipes 24 and a side wall 35 of the casing, 15 a lower vertical portion 36 located between the two sets of flue pipes, and a short horizontal connecting portion 37.

In the part of the chamber between the partition 33 and the side wall 39 of the casing are a set of horizontal flow directing members 40, 50, 60, 70. These members are staggered, the members 40 and 60 extending from the partition 33, and the members 50 and 70 extending from the side wall 39. In 20 the particular form illustrated, each flow directing member is formed in part by one of the trays 13. The lowest of these members, 40, consists of a horizontal partition 41, extending from the lower end of the partition 33, and the tray 13^a. The next flow directing member, 50, consists of a horizontal partition 51, extending from the wall 39, the tray 13^a, and a partition 52, extending from the end of this tray through the inner set of 25 flue pipes 25. The next, 60, is formed by a horizontal partition 61, extending from the partition 33 on the level with its horizontal portion 37, and the tray 13^a. The last flow directing member, 70, is formed by a horizontal partition 71, extending from the wall 39, the tray 13^a, and a partition 72 extending from the edge of this tray to and through the outer set of flue pipes 24.

It is apparent that the tortuous ascending 30 passage formed by the flow directing members just described has a bend 80, through which extend the lower portions 81 of the inner flue pipes 25, and another bend 90, through which extend the upper portions 91, 50 92 of both sets of flue pipes. These portions of flue pipes consequently serve as reheaters in the bends of the tortuous passage. It should be noted that the reheating thus provided by the flue pipes is approximately uniform, since the reheaters 81 in the bend 80 is hotter than the reheaters 91, 92 in the bend 90 but has a smaller radiating surface.

All parts of the flue pipes, except the portions 81, 91, 92 in the bends of the tortuous 60 passage, are used for the initial heating or preheating of the drying medium. Some preheating is caused in the conduit 16 by the extreme upper portions 82, 83 of the flue pipes. The principal preheating occurs in the lower half of the descending passage

31, where the drying medium is brought into contact with the lower portion 84 of the outer flue pipes 24 by staggered baffles 85, 86. Additional preheating is caused by the extreme lower portion 87 of the inner flue 70 pipes 25 and by the top 23 of the fire box.

In order to provide for separate and accurate control of the reheating in the bends 80 and 90 of the tortuous passage 32, by-pass openings 53, 73, 73' are provided in the partitions 52 and 72. The by-pass opening 53 may extend the whole length of the drier between the inner flue pipes 25 and the tray 13^a. It is controlled by a movable valve member or vane 54. The by-pass openings 73, 73' are located respectively between the inner flue pipes 25 and the tray 13^a, and between the two sets of flue pipes, and are controlled by valve members or movable vanes 74, 74'. The movable vanes 54, 74, 74' are fixed on hinge rods 45, 65, 65' pivotally mounted at the inner edges of the outer fixed portions 56, 76, 76' of the partitions 52 and 72. The vanes are provided with separate handles 57, 77, 77' projecting through the front wall of the drier, 80 so that the position of each vane may be controlled independently of the other vanes.

The regulation of the reheating of the drying medium, by means of the vanes 54, 74, 74', depends upon the fact that the amount of heat absorbed by the drying medium from each reheat is a function of the difference between the temperature of the drying medium in contact with the reheat and the temperature of the reheat itself, or more accurately of the flue gases within the reheat. The greater the temperature difference between the drying medium in contact with the reheat and the flue gases within it, the more rapidly is heat absorbed by the drying medium from the flue gases. Consequently, when the vane 54 is placed in closed or horizontal position, so that the entire stream of drying medium is brought into intimate contact with the reheat 81 formed by the lower portion of the inner flue pipes 25, a maximum amount of heat is absorbed by the stream from the flue gases within the reheat. When this vane is turned to a vertical position completely uncovering the by-pass opening 53, only a small part of the stream comes in contact with the reheat 81. As the volume of the part of the stream coming in contact with the reheat is small, this part of the stream rises in temperature 100 rapidly, and therefore absorbs comparatively little heat from the flue gases within the reheat. The other part of the stream which passes through the by-pass opening 53, and therefore is not reheated at all, mixes 110 with the part of the stream which has passed in contact with the reheat, thus making the average temperature of the stream above the flow directing member 50 less than was the case when the entire stream was brought into 115

120 the flow directing member 50 less than was the case when the entire stream was brought into 130

contact with the reheat. By setting the vane 54 in intermediate positions, the relative size of the two parts of the stream may be regulated, so as accurately to control the 5 extent to which the stream is reheated in passing around the bend 80, without making any change in the amount or temperature of the flue gases passing through the reheat.

The amount of reheating in the bend 90

10 may be controlled in a similar manner by means of the vanes 74 and 74', except in this case the control is even more accurate since the stream may be divided into three parts, one of which passes through the opening 73 15 which is not reheated, while the second passes over the flue pipes 25, and the third passes over these flue pipes and the outer flue pipes 24.

In the drier which has been described, the 20 outer fixed portions 56 and 76' of the partitions 52, 72, are not essential, and may be omitted without materially detracting from efficiency of the drier. Furthermore, it is not essential that the staggered overlapping 25 partitions and the bottom of the chamber be formed in part by the trays containing the material to be dried; and the reheating of the drying medium need not be limited to the bends of the tortuous passage at only one 30 side of the trays. The drier described is a very simple and efficient embodiment of the various features of my invention, but I wish it clearly understood that the invention is by no means limited to this specific embodiment.

What is claimed is:

1. In a drier, means providing a flow passage, means for causing a drying medium to flow through the passage, supports for the 40 material to be dried arranged in series in the passage, a plurality of reheaters in the passage, each located between two of said supports, individually adjustable means for regulating the proportion of the stream of drying medium brought into contact with each reheat, to control the reheating of the drying medium without varying the supply of heating medium to the reheat.

2. In a drier, means providing a flow passage, means for causing a drying medium to flow through the passage, supports for the material to be dried arranged in series in the passage, a continuous heating element extending through the flow passage at a plurality of 55 different points between said supports, separately adjustable means for regulating the proportion of the stream of drying medium brought into contact with the heating element at each such point, to control the reheating of the drying medium without varying the supply of heating medium to the heating element.

3. In a drier, a continuous wall enclosing a plurality of chambers open only at their 60 ends and pairs of passages connecting the

outlet end of each chamber with the inlet of the next chamber, means for supporting material to be dried within each of said chambers, means for causing a drying medium to flow through said chambers, a reheat in one 70 passage of each of said pairs of passages, a valve in the other passage of said each pairs of passages, and means for separately adjusting each of said valves.

4. In a drier, a continuous wall enclosing 75 a flow passage and a by-pass between two spaced points of said passage, means for causing a drying medium to flow through the passage, a first support for material to be dried located in the passage ahead of said by-pass, a second support for material to be dried located in the passage behind said by-pass, a reheat located in the passage between the said two points connected by said by-pass, and a valve located and movable 85 within the enclosed passage to control the by-pass.

5. In a drier, means providing a tortuous flow passage having closely spaced parallel straight portions connected by bends, means 90 for supporting the material to be dried in the straight portions of the flow passage, means for causing a drying medium to flow through the passage, reheaters located in bends of the passage, and separately adjustable means for by-passing a part of the stream of drying medium from the straight portion of the passage in front of each such bend to the next straight portion of the 95 passage.

6. In a drier, means providing a tortuous flow passage consisting of closely-spaced parallel straight portions connected by bends, means for causing a drying medium to flow through the passage, means for supporting 105 the material to be dried in the straight portions of the passage, a single heating element extending through a plurality of bends of the passage, and separately adjustable means for by-passing a part of the stream of drying 110 medium from the straight portion in front of each of said bends to the straight portion beyond it.

7. A drier having an enclosed chamber, a plurality of staggered overlapping flow directing members forming a continuous tortuous enclosed passage in said chamber, means for supporting the material to be dried between the overlapping portions of said flow directing members, a reheat located 115 between a side wall of the chamber and the end of one flow directing member, said flow directing member containing a by-pass opening between the material supports and said reheat, and a valve located and movable 120 within said enclosed passage to control said by-pass opening.

8. A drier having a chamber, a plurality of staggered overlapping flow directing members forming a continuous tortuous pas-

sage in the chamber, means for supporting the material to be dried between the overlapping portions of said flow directing members, a reheater located between a wall of the 5 chamber and the end of one of said flow directing members, a second reheater located between said first reheater and the material to be dried, said flow directing member containing by-pass openings located on opposite sides of said second reheater, and independently adjustable valves controlling said by-pass openings.

9. A drier having a chamber, staggered overlapping flow directing members forming a continuous tortuous flow passage in said chamber, a straight heating element at one side of the chamber passing through the flow directing members which extend to that side of the chamber and spaced from the ends 15 of the other flow directing members, movable vanes located between the ends of said other flow directing members and said heating element, and an independent means for regulating the position of each of said vanes.

10. A drier having a chamber, staggered overlapping horizontal flow directing members forming a continuous tortuous flow passage in said chamber, a fire box below the chamber, a vertical flue pipe extending from 20 said fire box upwardly in the chamber along one side thereof, and movable vanes located between said heating pipe and the ends of the partitions which extend from the opposite wall of the chamber.

11. A drier having means providing a passage, a plurality of supports for the material to be dried arranged in series in said passage, means for causing a drying medium to flow through said passage, a fire box, and a plurality of flue pipes extending from said fire box, portions of some of said pipes near the fire box passing across the flow passage to reheat the drying medium between two of its contacts with the material to be dried, 45 and portions of a greater number of said pipes further from the fire box passing across said passage at another point to cause a similar reheating of the drying medium between two other of its contacts with the material to be dried.

12. A drier having means providing a passage, a plurality of supports for the material to be dried arranged in series in said passage, means for causing a drying medium to flow 55 through said passage, a fire box, a plurality of flue pipes extending from said fire box, portions of some of said pipes near the fire box passing across the flow passage to reheat the drying medium between two of its contacts with the material to be dried, and portions of a greater number of said pipes further from the fire box passing across said passage at another point to cause a similar reheating of the drying medium between two other of its contacts with the ma-

terial to be dried, and means for utilizing the portions of said pipes which are not within the flow passage to heat the drying medium before it enters the flow passage.

13. A drier having a chamber, a fire box 70 below said chamber, a plurality of vertical pipes conducting the products of combustion from said heater through the chamber, flow directing members in the chamber providing a tortuous passage having straight 75 portions containing the material to be dried and a bend which encloses a lower portion of some of said heating pipes and another bend which encloses an upper portion of a greater number of said heating pipes, and 80 means for causing a drying medium to flow through said passage.

14. A drier having a chamber, a fire box 85 below said chamber, a plurality of vertical pipes conducting the products of combustion from said heater through the chamber, flow directing members in the chamber providing a tortuous passage having straight 90 portions containing the material to be dried and a bend which encloses a lower portion of some of said heating pipes and another bend which encloses an upper portion of a greater number of said heating pipes, and means for causing a drying medium to flow over the portions of said pipes not within 95 said flow passage and then through the flow passage.

15. A drier having a chamber, staggered overlapping horizontal flow directing members forming a continuous tortuous flow passage in the chamber, means for supporting the material to be dried between the overlapping portions of said flow directing members, a gas heater below the chamber, vertical flue pipes extending from said gas 100 heater to the top of the chamber through the bends of said tortuous flow passage to reheat the drying medium between its contacts with the material to be dried.

16. A drier comprising a chamber having 110 inlet and outlet openings at its top, a gas heater located below the chamber, two sets of vertical flue pipes extending from the heater through the chamber near one of its side walls, supports for the material to be 115 dried located in the central part of the chamber, means for forcing a drying medium into the inlet opening of the chamber, and means for directing said drying medium downwardly in a zig-zag path across the outer set 120 of flue pipes to the bottom of the chamber and then upwardly in a zig-zag path across the material supports and around the inner set of pipes.

17. The method of drying which comprises 125 dividing the material to be dried into separate masses, causing a stream of heated drying medium to flow across one of the masses, then dividing said stream into separate parts, reheating one part of said stream, re- 130

uniting the parts of said stream, and causing the stream to flow over the next mass of the material.

18. In the method of drying which comprises causing a heated stream of drying medium to flow across alternately arranged re-heaters and masses of the material to be dried, the method of regulating the degree

to which the stream is reheated between its successive contacts with the successive masses which consists in by-passing a regulated proportion of the stream around each of the re-heaters.

In testimony whereof I have hereunto set my hand.

DAVID S. BAKER.
